Primary Examiner — Mark A Goodwin(74) *Attorney, Agent, or Firm* — WHDA, LLP(57) **CLAIM**

The ornamental design for an electrically-powered snowplow, as shown and described.

DESCRIPTION

FIG. 1 is a first perspective view of an electrically-powered snowplow, showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines shown in the drawings depict portions of the electrically-powered snowplow that form no part of the claimed design.
